UNITED STATES PATENT OFFICE.

FREDERICK GOERTZ, OF MAPLEWOOD, NEW JERSEY, ASSIGNOR TO AUGUST GOERTZ & CO., INC., A CORPORATION OF NEW JERSEY.

RECEPTACLE.

Application filed October 8, 1925. Serial No. 61,209.

This invention relates, generally to improvements in that class of cases or boxes known in the art as vanity boxes; and, the present invention has reference, more particularly, to a novel and simply constructed vanity box or case, comprising a compartment or chamber adapted to contain loose face-powder, and an opening for application of some of the powder to a powder-puff 10 or other means for applying the powder to the face, the chamber being also provided with a movable shaker or agitating means for producing a loose condition of the face-powder for its proper application to the 15 powder-puff or other applying means; and, furthermore, to prevent caking of the face-powder, when not in constant use.

The invention has for its principal object to provide a neat and simply constructed 20 vanity box or case for the purposes hereinabove stated, and in which all of the various members thereof are secured and maintained in assembled relation to produce a thin and a neat structure when the parts of the box 25 are in their closed relation.

The invention has for its further object to provide a simple cover-insert for the face-powder containing compartment or chamber which is readily removed for the addition 30 of a fresh supply of the face-powder, and is easily and quickly snapped into place when the chamber or compartment has received a fresh supply of the face-powder.

Other objects of this invention not at this 35 time more particularly enumerated, will be fully understood from the following detailed description of the present invention.

With the various objects of the present invention in view, the said invention consists, 40 primarily, in the novel vanity case or box hereinafter more fully set forth; and, the said invention consists, furthermore, in the novel arrangements and combinations of the various devices and parts, as well as in the 45 details of the construction of the said parts, all of which will be more fully described in the following specification, and then finally embodied in the clauses of the claims which are appended to, and which form an essential 50 part of the specification.

The invention is illustrated in the accompanying drawings, in which:—

Fig. 1 is a plan view of a vanity case or box

made according to and embodying the principles of the present invention, said view 55 showing the main lid or cover of the case in its opened position, and showing in connection therewith an auxiliary lid in its closed position above the powder-containing chamber of the device; Fig. 2 is a similar 60 view of the said vanity case or box, showing both said main lid and the said auxiliary lid in their opened positions, and illustrating more particularly the arrangement of 65 the perforated insert disposed directly above the powder within the powder-containing chamber; and Fig. 3 is another plan view of the vanity box or case, with the said insert and auxiliary lid shown removed from within the main shell of the box or case, and 70 showing in connection with the powder-containing chamber, one arrangement of shaker or agitating means.

Fig. 4 is a vertical sectional representation 75 of the device, said section being taken on line 4—4 in Fig. 1; and Fig. 5 is a horizontal section of the same, taken on line 5—5 in said Fig. 4.

Fig. 6 is a plan view of the insert and auxiliary lid hinged thereto, shown removed 80 from the main shell of the vanity-box or case; Fig. 7 is a plan view of one form of shaker or agitating means, also shown removed from the said main shell; and Fig. 8 is a side elevation of the vanity box or case. 85

Similar characters of reference are employed in all of the said above described views, to indicate corresponding parts.

Referring now to the several figures of the drawings, the reference-character 1 indicates a main body or shell of any suitable configuration, the said body or shell comprising a base 2 bounded by a marginal wall 3. The upper edge-portion of this wall 3 is bounded by an annular off-set portion 4, 95 and an inwardly extending annular portion 5, said portion 5 in turn being bounded by a downwardly extending portion or shoulder 6 provided at its lower edge with an inwardly 100 extending portion 7, substantially as shown in Fig. 4 in the drawings. This annular portion 7 forms a suitable seat, for the purpose to be presently described, and diametrically opposite each other, the said downwardly extending portion or shoulder 6 is 105 provided with suitable openings or perfora-

tions, preferably in the form of slits, as 8 and 9. Pivotally connected with the wall 3 by means of a hinge 10, or in any other suitable manner, is the annular flange 12 of a 5 lid or cover 11, which flange, when the lid or cover is closed down, enters directly over the inwardly extending annular portion 5, so as to rest upon the annular seat formed by the off-set portion 4, as will be evident. 10 The said lid or cover is suitably maintained in its closed relation with the main body or shell, in any suitable manner, by means of locking or retaining members, as 13 and 14, the member 13 being of such shape that it 15 will also serve as a fingerpiece for lifting the lid or cover out of its holding engagement with the lock-stud or teat 14, as will be evident. Extending outwardly from the wall 3, at a point beneath the said stud or 20 teat 14, there may also be a projection, as 15, which serves as a thumb-piece or finger-hold serving as a means which facilitates easy manipulation of the device, so as to readily bring the lid or cover into its opened 25 or closed relation with the said main body or shell of the device. Suitably disposed within the chamber formed by the base 2 and wall 3 of the said main body or shell is a dished or other suitably shaped powder-retaining element or member 16, formed with 30 a centrally disposed opening, as 17, and with an outwardly extending annular flange 18 adapted to be seated upon the seat formed by the previously mentioned annular portion 7. Extending downwardly from the 35 marginal portion 19, which bounds the opening 17 of the retaining element or member 16, are a series of downwardly extending lugs or studs, as 20, which are adapted to 40 rest upon the upper face of the base 2, so as to provide suitable openings 21 through which the face-powder 22 is passed from the main chamber of the device to the opening 17 of the retaining element or member 16, in the 45 manner and for the purposes to be presently more fully described. The said retaining element or member is also removably maintained in its powder-retaining position within the said main body or shell 1 by the provision of a stud or projection 23 which extends laterally from the flange 18 and is adapted to be inserted in the slit 8 of the shoulder 6, and with a projection or nosing, as 24, which is adapted to be sprung into the 50 opening or slit 9 at the opposite side of the shoulder 6, the said element or member 16 being also provided with an upwardly projecting member 25, suitably bent so as to provide a finger-piece for lifting the said element or member 16 into its raised position or for closing it down within the main body or shell 1, as may be desired. The upper open portion 26 of the said element or member 16 is also desirably closed by 55 means of a lid 27, suitably hinged to the

said element or member 16, as at 28, and held in its closed position by a projection, as 29, adapted to be sprung into an opening or slit 30, also formed in the upper portion 26 of the said member or element 16. The said lid 27 is also provided with an upwardly projecting member 31, suitably bent so as to provide a fingerpiece for bringing the said lid 27 into its opened or closed relation with the said retaining element or member 16, as 70 will be understood from an inspection of Figures 1 and 2 of the drawings. As a means of forcing the face-powder through the previously mentioned openings 21 to the open space formed by the opening 17 of the 75 element or member 16, a shaking or agitating device, usually in the form of a ring 32, movably disposed upon the inner face of the base 2 is provided, this ring being of such shape and operating in such a manner, that 80 when the operator shakes the vanity box or case a corresponding movement of the ring is also produced, the ring cutting through the powder, and forcing the desired quantity 85 through the openings 21 into the open 90 space formed by the opening 17 of the retaining element or member 16, as will be fully understood from an inspection more particularly of Figures 3, 4 and 5 of the 95 drawings.

From the foregoing description of the present invention, it will be clearly seen, that I have provided a neat and compact assemblage of the various elements comprising the vanity case or box, the said various elements being easily and quickly assembled and maintained in their assembled relation without the employment of solder, rivets or the like.

Of course I am fully aware, that changes 105 may be made in the general arrangements and combinations of the various devices and parts, as well as in the details of the construction of the said parts, without departing 110 from the scope of the present invention 115 as set forth in the foregoing specification, and as defined in the clauses of the claims which are appended thereto. Hence, I do not limit my present invention to the exact arrangements and combinations of the various devices and parts, as described in the 120 said specification, nor do I confine myself to the exact details of the construction of the said parts, as illustrated in the accompanying drawings.

I claim:—

1. A receptacle comprising a body adapted to receive a powder, a retaining element within said body, said retaining element having a depressed centrally open portion forming a powder-delivery opening, said retaining element being further provided with depending lugs adjacent said opening, said lugs engaging with the base of the body and providing intermediate spaces for delivery 130

of the powder to said opening, and agitator means freely movable in the bottom of said body between its sides and said lugs.

2. A receptacle comprising a body adapted to receive a powder, a retaining element within said body, said retaining element having a depressed centrally open portion forming a powder-delivery opening, and said retaining element being further provided with depending lugs adjacent said opening, said lugs engaging with the base of the body and providing intermediate spaces for delivery of the powder to said opening, a lid hinged to said retaining element, and agitator means freely movable on the bottom of said body between its sides and said lugs.

3. A receptacle comprising a body adapted to receive a powder, a retaining element within said body, said retaining element having an open portion forming a powder-delivery opening, and an agitator-ring within said body and movably disposed beneath said retaining element.

4. A receptacle comprising a body adapted to receive a powder, a retaining element within said body, said retaining element having an open portion forming a powder-delivery opening, and said retaining element being further provided with lugs adjacent said opening, said lugs forming with the base of the body spaces for delivery of the powder to said opening, and an agitator-ring within said body and movably disposed beneath said retaining element.

5. A receptacle comprising a body adapted to receive a powder, a retaining element within said body, said retaining element having an open portion forming a powder-delivery opening, associated with a lid hinged to said retaining element, and an agitator-ring within said body and movably disposed beneath said retaining element.

6. A receptacle comprising a body adapted to receive a powder, a retaining element within said body, said retaining element having an open portion forming a powder-delivery opening, and said retaining element being further provided with lugs adjacent said opening, said lugs forming with the base of the body spaces for delivery of the powder to said opening, associated with a lid hinged to said retaining element, and an agitator-ring within said body and movably disposed beneath said retaining element.

7. A receptacle comprising a body adapted to receive a powder, said body having an annular wall provided with an inwardly extending flange having a marginal off-set forming a seat, said seat being provided with a lug-receiving opening, a retaining element upon said seat, said retaining element having an open portion forming a powder-delivery opening, a lug projecting from said retaining element and extending into said lug-receiving opening for movably dispos-

ing said retaining element upon said seat, and retaining means associated with said retaining element and the flanged portion of said body for maintaining the retaining element in its closed relation with said body.

8. A receptacle comprising a body adapted to receive a powder, said body having an annular wall provided with an inwardly extending flange having a marginal off-set forming a seat, said seat being provided with a lug-receiving opening, a retaining element upon said seat, said retaining element having an open portion forming a powder-delivery opening, a lug projecting from said retaining element and extending into said lug-receiving opening for movably disposing said retaining element upon said seat, retaining means associated with said retaining element and the flanged portion of said body for maintaining the retaining element in its closed relation with said body, and said retaining element being further provided with lugs adjacent said opening, said lugs forming with the base of the body spaces for delivery of the powder to said opening.

9. A receptacle comprising a body adapted to receive a powder, said body having an annular wall provided with an inwardly extending flange having a marginal off-set forming a seat, said seat being provided with a lug-receiving opening, a retaining element upon said seat, said retaining element having an open portion forming a powder-delivery opening, a lug projecting from said retaining element and extending into said lug-receiving opening for movably disposing said retaining element upon said seat, retaining means associated with said retaining element and the flanged portion of said body for maintaining the retaining element in its closed relation with said body, and associated further with a lid hinged to said retaining element.

10. A receptacle comprising a body adapted to receive a powder, said body having an annular wall provided with an inwardly extending flange having a marginal off-set forming a seat, said seat being provided with a lug-receiving opening, a retaining element upon said seat, said retaining element having an open portion forming a powder-delivery opening, a lug projecting from said retaining element and extending into said lug-receiving opening for movably disposing said retaining element upon said seat, retaining means associated with said retaining element and the flanged portion of said body for maintaining the retaining element in its closed relation with said body, and said retaining element being further provided with lugs adjacent said opening, said lugs forming with the base of the body spaces for delivery of the powder to said opening.

11. A receptacle comprising a body adapted to receive a powder, said body having an annular wall provided with an inwardly extending flange having a marginal off-set forming a seat, said seat being provided with a lug-receiving opening, a retaining element upon said seat, said retaining element having an open portion forming a powder-delivery opening, a lug projecting from said retaining element and extending into said lug-receiving opening for movably disposing said retaining element upon said seat, retaining means associated with said retaining element and the flanged portion of said body for maintaining the retaining element in its closed relation with said body, and said retaining element being further provided with lugs adjacent said opening, said lugs forming with the base of the body spaces for delivery of the powder to said opening, and associated further with a lid hinged to said retaining element.

11. A receptacle comprising a body adapted to receive a powder, said body having an annular wall provided with an inwardly extending flange having a marginal off-set forming a seat, said seat being provided with a lug-receiving opening, a retaining element upon said seat, said retaining element having an open portion forming a powder-delivery opening, a lug projecting from said retaining element and extending into said lug-receiving opening for movably disposing said retaining element upon said seat, retaining means associated with said retaining element and the flanged portion of said body for maintaining the retaining element in its closed relation with said body, and agitator-means within said body and movably disposed beneath said retaining element.
12. A receptacle comprising a body adapted to receive a powder, said body having an annular wall provided with an inwardly extending flange having a marginal off-set forming a seat, said seat being provided with a lug-receiving opening, a retaining element upon said seat, said retaining element having an open portion forming a powder-delivery opening, a lug projecting from said retaining element and extending into said lug-receiving opening for movably disposing said retaining element upon said seat, retaining means associated with said retaining element and the flanged portion of said body for maintaining the retaining element in its closed relation with said body, said retaining element being further provided with lugs adjacent said opening, said lugs forming with the base of the body spaces for delivery of the powder to said opening, and associated further with a lid hinged to said retaining element, and agitator-means within said body and movably disposed beneath said retaining element.
13. A receptacle comprising a body adapted to receive a powder, said body having an annular wall provided with an inwardly extending flange having a marginal off-set forming a seat, said seat being provided with a lug-receiving opening, a retaining element upon said seat, said retaining element having an open portion forming a powder-delivery opening, a lug projecting from said retaining element and extending into said lug-receiving opening for movably disposing said retaining element upon said seat, retaining means associated with said retaining element and the flanged portion of said body for maintaining the retaining element in its closed relation with said body, associated further with a lid hinged to said retaining element, and agitator-means within said body and movably disposed beneath said retaining element.
14. A receptacle comprising a body adapted to receive a powder, said body hav-
- ing an annular wall provided with an inwardly extending flange having a marginal off-set forming a seat, said seat being provided with a lug-receiving opening, a retaining element upon said seat, said retaining element having an open portion forming a powder-delivery opening, a lug projecting from said retaining element and extending into said lug-receiving opening for movably disposing said retaining element upon said seat, retaining means associated with said retaining element and the flanged portion of said body for maintaining the retaining element in its closed relation with said body, said retaining element being further provided with lugs adjacent said opening, said lugs forming with the base of the body spaces for delivery of the powder to said opening, and associated further with a lid hinged to said retaining element, and agitator-means within said body and movably disposed beneath said retaining element.
15. A receptacle comprising a body adapted to receive a powder, said body having an annular wall provided with an inwardly extending flange having a marginal off-set forming a seat, said seat being provided with a lug-receiving opening, a retaining element upon said seat, said retaining element having an open portion forming a powder-delivery opening, a lug projecting from said retaining element and extending into said lug-receiving opening for movably disposing said retaining element upon said seat, retaining means associated with said retaining element and the flanged portion of said body for maintaining the retaining element in its closed relation with said body, and an agitator-ring within said body and movably disposed beneath said retaining element.
16. A receptacle comprising a body adapted to receive a powder, said body having an annular wall provided with an inwardly extending flange having a marginal off-set forming a seat, said seat being provided with a lug-receiving opening, a retaining element upon said seat, said retaining element having an open portion forming a powder-delivery opening, a lug projecting from said retaining element and extending into said lug-receiving opening for movably disposing said retaining element upon said seat, retaining means associated with said retaining element and the flanged portion of said body for maintaining the retaining element in its closed relation with said body, said retaining element being further provided with lugs adjacent said opening, said lugs forming with the base of the body spaces for delivery of the powder to said opening, and an agitator-ring within said body and movably disposed beneath said retaining element.
17. A receptacle comprising a body adapt-

- ed to receive a powder, said body having an annular wall provided with an inwardly extending flange having a marginal off-set forming a seat, said seat being provided 5 with a lug-receiving opening, a retaining element upon said seat, said retaining element having an open portion forming a powder-delivery opening, a lug projecting from said retaining element and extending 10 into said lug-receiving opening for movably disposing said retaining element upon said seat, retaining means associated with said retaining element and the flanged portion of said body for maintaining the retaining element in its closed relation with said body, 15 associated further with a lid hinged to said retaining element, and an agitator-ring within said body and movably disposed beneath said retaining element.
18. A receptacle comprising a body adapted 20 to receive a powder, said body having an annular wall provided with an inwardly extending flange having a marginal off-set forming a seat, said seat being provided 25 with a lug-receiving opening, a retaining element upon said seat, said retaining element having an open portion forming a powder-delivery opening, a lug projecting from said retaining element and extending
- into said lug-receiving opening for movably disposing said retaining element upon said seat, retaining means associated with said retaining element and the flanged portion of said body for maintaining the retaining element in its closed relation with said body, 30 associated further with a lid hinged to said retaining element being further provided with lugs adjacent said opening, said lugs forming with the base of the body spaces for delivery of the powder to said opening, associated further with a lid hinged to said retaining element, and an agitator-ring within said body and movably disposed beneath said retaining element. 35
19. A dished retaining element for a vanity-case provided in its dished portion with 40 an opening, and having a marginal off-set forming a seat, a lid hinged to said element, and retaining means associated with said lid and retaining element for maintaining a closed relation of the lid with the retaining element, said retaining element being further provided with lugs adjacent said opening to provide delivery spaces between said lugs. 45

In testimony, that I claim the invention 50 set forth above I have hereunto set my hand this first day of Oct., 1925.

FREDERICK GOERTZ.
